[57] CLAIM

The ornamental design for a combined hanging ornament and sign, as shown and described.

DESCRIPTION

FIG. 1 is a front elevational view combined hanging ornament and sign showing my new design a mirror image, and with the broken line showing for illustrative purposes only and not forming a part of the claimed design;

FIG. 2 is a top plan view thereof; and,

FIG. 3 is a bottom plan view thereof.

FIG. 1

FIG. 3
